Des. 183,488
Patented Sept. 9, 1958

183,488

WRIST WATCH OR SIMILAR ARTICLE

Nathan G. Horwitt, Lenox, Mass.

Application October 25, 1954, Serial No. 32,813

Term of patent 14 years

(Cl. D42—8)

FIG. 1

FIG. 2

Fig. 1 is a front perspective view of a wrist watch showing my new design; and

Fig. 2 is an enlarged front elevational view thereof with the strap portion being omitted for convenience of illustration.

The dominant features of my design reside in the portion shown in full lines in the drawing.

The design is characterized by the contrast in appearance between the dot, the watch bands, and the dial face.

I claim:

The ornamental design for a wrist watch or similar article, substantially as shown and described.
